ABSTRACT

A rotary piston expander engine of the trochoidal type is described wherein the four phases of an expander cycle, i.e., intake, expansion, exhaust and recompression, are performed in a working chamber without using any external valving. A compressible working fluid at high temperature and pressure is injected in the working chamber during the intake phase by proper alignment of a passage through the output shaft and eccentric, a slot in a bushing serving as a rotor-eccentric bearing, and one of the slots in the rotor flanks. A face seal is used to interface the rotating shaft with a source of the working fluid. Exhaust phase is also accomplished without external valving by properly aligning a rotor side seal passage over ports in the end plates of the working chamber.

VALVELESS ROTARY PISTON EXPANSION ENGINE

STATEMENT OF GOVERNMENT INTEREST

The invention described herein may be manufactured and used by or for the Government of the United States of America for governmental purposes without the payment of any royalties thereon or therefor.

BACKGROUND OF THE INVENTION

This invention relates to rotary piston engines and more specifically to a valveless rotary piston positive displacement expansion engine of trochoidal type.

The rotary piston engine originally patented by F. Wankel for internal combustion application serves as the basic rotary piston engine. One interesting feature of the Wankel rotary piston engine is that the output shaft rotates at three times the speed of the rotor with respect to the housing. This characteristic allows a point on the shaft-eccentric to align in succession with each of the three rotor flanks when each flank is in a position where the working chamber has minimum volume. Many modifications have been made to the basic rotary engine. However, the requirements to transfer the working fluid into and out of the engine impose additional design and operational complexities whenever external valves are employed. Thus it has been considered desirable to have a rotary piston engine in which a separately driven external valving is eliminated for the intake phase and exhaust phase of the expander cycle during the operation of such a machine.

SUMMARY OF THE INVENTION

The objects and advantages of the present invention are accomplished by utilizing a rotary piston positive displacement expander engine wherein the four phases of an expander cycle, i.e., intake, expansion, exhaust and recompression, are performed without any external valving in a working chamber which moves with the rotary piston inside a two-lobe trochoidal outer housing. A compressible working fluid at high temperature and pressure from an external source is introduced during the intake phase by proper alignment of a drilled passage through the output shaft and eccentric, a slot in a bushing serving as the rotor-eccentric bearing and a slot in one of the rotor flanks, thus eliminating external valving during the intake phase of the cycle. Exhaust phase of the expander cycle is also accomplished by timing rotor side seal passage over the ports in the end plates of the working chamber.

An object of this invention is to have a rotary piston positive displacement expander engine wherein intake phase of an expander cycle of the engine is performed by introducing a working fluid into a working chamber without any external valving.

Another object is to have a rotary piston positive displacement expander engine wherein exhaust phase of the expander cycle after the expansion phase is accomplished without any external valving.

Still another object is to have a rotary piston engine wherein the working chamber, where expander cycles are performed, moves with the rotary piston inside a two-lobe trochoidal outer housing.

Still another object is to have a rotary piston engine wherein the length of a rotor slot controls the duration of the intake phase.

Still another object is to have a rotary piston engine wherein a rotating shaft-eccentric is interfaced with an external source of working fluid by means of a face seal.

Other objects, advantages and novel features of the invention will become apparent from the following detailed description of the invention when considered in conjunction with the accompanying drawings wherein:

BRIEF DESCRIPTION OF THE DRAWINGS

FIG. 1 is a cross-sectional view of the working chamber of the rotary piston positive displacement expander engine including a showing of intake passage and exhaust passage;

FIG. 2 shows the relative positions of the shaft-eccentric, the bushing, and the rotor;

FIG. 3 is a diagrammatic representation of the working chamber, the position of the rotor and the shaft-eccentric at the start of an intake phase (top portion) of the expander cycle;

FIG. 4 is a diagrammatic representation of the position of the working chamber, the rotor, and the shaft-eccentric at the cut-off portion of the expander cycle;

FIG. 5 is a diagrammatic representation of the position of the working chamber, the rotor, and the shaft-eccentric during the intake phase (bottom portion) of the expander cycle;

FIG. 6 is a diagrammatic representation of the position of the working chamber during the exhaust phase of the expander cycle; and

FIG. 7 shows the shape of the exhaust ports of the rotary piston engine.

DESCRIPTION OF A PREFERRED EMBODIMENT

Referring to the drawings wherein like reference characters designate like parts throughout the several figures, and more particularly to FIG. 1 thereof, a rotary piston positive displacement expander engine is shown. The expander engine comprises a working chamber 10 in housing 11 which is enclosed on both ends by means of end plates 12 and 14 and the use of through bolts such as through bolt 16. Attached to the end plate 12 is a tubing 18 provided with a flange 20 which is fastened to end plate 12 by means of bolts 22 and 24. Shaft 26 has its end 28 passing through end plate 14 and has its end 30 passing through end plate 12 and housing in tubing 18. Shaft 26 has an eccentric part 32 housed in the working chamber 10 which also houses rotor 34. Rotor 34 is provided with a bushing 36 having a slot or opening 38 in it. Bushing 36 is made of a solid lubricant such as graphite, which serves to provide cut off or closure of the eccentric passage. End 40 of tubing 18 has a passage or opening 42 for an intake connection to a stationary external source of a compressible working fluid at high temperature and pressure. Passage or opening 42 in tubing 18 extends throughout its length. A face seal 44 is housed near end 40 of the tubing 18 and is spring-loaded by means of spring 46 as shown in FIG. 1. Passage or opening 42 is in communication with passage or opening 48 of the face seal which in turn is in communication with passage or opening 50 in shaft 26. Passage 50 extends to nearly the center part of the working chamber and is continued through eccentric portion 32 of the shaft 26 as passage or opening 52. Passage or opening 52 is alignable with slot 38 of the bushing 36 and also alignable with a slot or opening such as opening 54 of rotor

34. The relative positions of shaft-eccentric 26, bushing 36, and rotor 34 are shown in FIG. 2. Bushing 36 is permanently attached to rotor 34.

When passages 42, 48, 50, 52, 38 and 54 are aligned and are in communication, the working fluid is admitted to the working chamber 10 therethrough during the intake phase of the expander cycle (top portion). The position of shaft 26 and its eccentric piece 32, rotor 34 and bushing 36 is shown in FIG. 3 wherein passages 42, 52, 38 and 54 are in communication with one another. As can be seen from FIG. 3, flank 56 of rotor 34 is in the upper portion of the working chamber 10 enclosing a minimum portion of the space in the working chamber 10. It should be noted that the rotating shaft-eccentric unit 26 is interfaced with the stationary fluid source by face seal 44. The motion of rotor 34 is so timed that the working fluid is introduced in the working chamber 10 at minimum volume positions as shown in FIGS. 3 and 5. FIG. 5 represents that part of the intake cycle where flank 58 is in such a position as to offer minimum volume for the intake of working fluid. As can be seen from FIGS. 3, 4 and 5, the relative motion between the rotor 34 and shaft-eccentric 26 allows the working fluid to be introduced every time one of the rotor slots 54, 62 and 64 in rotor flanks 56, 58 and 60 respectively comes to a position to offer minimum volume to the working fluid. FIG. 4 represents that part of the expander cycle wherein passage 50 is out of communication with rotor slot 54, and thus represents cut-off phase of the expander cycle. FIG. 6 shows the sealing grid of the working chamber wherein side seals on rotor 34 are used to uncover parts in the end plates 12 and 14 of the engine to allow for exhaustion of the expanded working fluid. Arrow 69 shows the direction of rotation of rotor 34 during an expander cycle of the engine. The triangularly-shaped ports 66 and 68 are so located and sized to provide the desired exhaust phase. As an example, line 70 might be determined by the rotor side seal position at maximum expansion. Line 72 represents the rotor side seal position at desired exhaust closure and line 74 is any line that will not interfere with the engine functions and it determines the maximum exhaust area.

Briefly stated, in the rotary piston positive displacement expander engine built according to the teachings of this invention, intake phase of an expander cycle is accomplished by introducing the working fluid through one of rotor slots in rotor faces or flanks by means of a drilled passage through the output shaft and eccentric and where a slotted bushing serves as a bearing between the rotor and eccentric and allows passage of working fluid to a corresponding rotor slot. The intake process continues until the eccentric passage has moved the entire length of one of the rotor slots after which it is stopped by the eccentric-rotor bushing. Further rotation causes the eccentric to come into a position to fill another rotor flank which has reached a position wherein the working chamber had minimum volume. Side seals on the rotor are used to uncover ports in the end plates for exhaustion of the expanded working fluid. The length of the rotor slots controls the duration of the intake phase, the location of the eccentric passage in relation to the rotor slots at minimum volume of the working chamber determines the start of the intake phase, and the bushing serves to provide cut-off or closure of the eccentric passage or opening. The pas-

sage of the side seal of the rotor controls the opening and closing of the side port.

Obviously many modifications and variations of the present invention are possible in the light of the above teachings. As an example, a solid lubricant other than graphite may be used for the bushing serving as the rotor-eccentric bearing. Alternatively, some other arrangements such as a rolling element bearing or a hydrodynamic bearing may also be used. Furthermore, an arrangement other than a face seal may be used to interface the rotating shaft-eccentric with the external stationary source of a working fluid. It is therefore understood that within the scope of the appended claims the invention may be practiced otherwise than as specifically described.

We claim:

1. A valveless rotary piston engine of the external combustion and open cycle type having a rotor with multiple flanks and side seals and mounted on a shaft-eccentric for rotational motion within a housing enclosed by a first end-plate and a second end-plate and defining a working chamber of variable volume during the rotation of said rotor by introduction of a gaseous working fluid at relatively high pressure and temperature in said working chamber, an improved means for controlling the introduction of said working fluid in said working chamber from an external source thereof which comprises:

a first passage through said shaft eccentric for receiving said working fluid from said external source; a second passage through said rotor and a bushing attached to said rotor, said bushing having a first plurality of slots and said bushing serving as a rotor-shaft eccentric bearing, said second passage being in and out of alignment with first passage during the rotation of said rotor;

a second plurality of slots in said rotor, each of said multiple flanks of said rotor having at least one slot of said second plurality of slots, each slot of said first plurality of slots in said bushing being aligned with a corresponding slot of said second plurality of slots in said rotor; and

a pair of exhaust ports in said second end-plate, each one of said pair of exhaust ports being covered and uncovered in succession during the rotation of said rotor.

2. The improved means of claim 1 for controlling the introduction of said working fluid into said working chamber wherein said first passage, said second passage and one of said plurality of slots in said rotor are in alignment during an intake phase of an expander cycle of said valveless engine to allow said working fluid in said working chamber.

3. The improved means of claim 1 for controlling the introduction of said working fluid into said working chamber wherein said working chamber is in communication with one of said pair of exhaust ports during an exhaust phase of the expander cycle of said valveless engine to expel working fluid from said working chamber.

4. The improved means of claim 1 for controlling the introduction of said working fluid into said working chamber wherein said first passage in said shaft-eccentric is interfaced with said source of said working fluid by means of a face seal.

5. The improved means of claim 1 for controlling the introduction of said working fluid into said working chamber wherein said bushing is made of a solid lubricant.

6. The improved means of claim 5 for controlling the introduction of said working fluid into said working chamber wherein said solid lubricant for making said bushing is graphite.
